UNITED STATES PATENT OFFICE.

AMBROSE F. WERTMAN, OF HUMMELSTOWN, PENNSYLVANIA.

EDGE-TRIMMER.

1,231,464.

Specification of Letters Patent. Patented June 26, 1917.

Application filed November 24, 1916. Serial No. 133,136.

To all whom it may concern:

Be it known that I, AMBROSE F. WERTMAN, a citizen of the United States, and a resident of Hummelstown, in the county of 5 Dauphin and State of Pennsylvania, have invented a certain new and useful Improvement in Edge-Trimmers, of which the following is a specification.

My invention relates to improvements in 10 edge trimmers, more especially in those devices which are used in trimming the edges of the soles of shoes, and it consists in the combinations, constructions, and arrangements herein described and claimed.

An object of my invention is to provide a 15 device by means of which the edge of a sole may be trimmed smoothly, that is to say, will be trimmed without the undulations which the cutter usually makes due to the 20 vibration of the shaft on which the cutter is secured.

A further object of my invention is to provide a device which prevents the vibration of the shaft, thus enabling the cutter to make 25 a smooth cut which it otherwise would not make, and at the same time forms a protecting guard which prevents the workman from receiving an injury from the cutter during the operation of the latter.

30 A further object of my invention is to provide an attachment to the ordinary edge trimming machine, which will accomplish the foregoing objects and which may be applied in a few minutes.

35 Other objects and advantages will appear in the following specification, and the novel features of the invention will be particularly pointed out in the appended claims.

My invention is illustrated in the accompanying drawing forming part of this specification, in which:

Figure 1 is a face view of an edge trimmer embodying my improved invention, and

Fig. 2 is a longitudinal section, enlarged, 45 along the line 2-2 of Fig. 1.

In carrying out my invention I make use of certain parts of the ordinary edge trimmer, these parts including a supporting base A, bearings B and C carried by the base, a 50 pulley D mounted on a shaft E, and a belt F for driving the pulley. As stated above these parts are ordinary. The bearing B has an extension b and, as will be seen from Fig. 2, a cutter K is secured to 55 the end of the shaft E at some distance beyond the end of the extension b. The cutter

K forms no part of the present invention, except so far as it coöperates with the novel features hereinafter described.

Secured to the end of the extension b of 60 the bearing B is a sleeve G, which surrounds the shaft E and which is provided with an enlarged portion g arranged to fit over the end of the extension b, this portion g being preferably split and being provided with 65 ears g² through which a screw bolt g³ extends. The purpose of the screw bolt is to clamp the sleeve G securely to the end of the extension b.

Slidably disposed on the sleeve G is a 70 second sleeve H, which is held to the sleeve G by means of a set screw S. The position of the sleeve H with respect to the sleeve G may be varied by loosening the set screw and shifting the sleeve G to the desired position, and then tightening up on the screw. 75 As will be seen from the drawing the sleeve H is provided with a flange h which extends over one edge of the cutter K.

From the foregoing description of the 80 various parts of the device, the operation thereof may be readily understood.

The edge of the sole of the shoe is held against the cutter in the space P between the edge of the flange h and a circular flange 85 T on the opposite side of the cutter. The edge of the sole is run along the cutter in a well known manner, and the revolution of the cutter trims the edge.

Now the trouble with the edge trimmers 90 heretofore was that the shaft E near the cutter had no means of support so that the shaft would vibrate laterally of its axis, thereby making a series of ridges or undulations in the edge of the sole, instead of making a smooth cut. Moreover, the guard which kept the workman from being injured revolved with the cutter, and inasmuch as the guard had teeth which entered between the teeth of the cutter, many times a workman would be injured by the rapidly moving guard itself.

In the present instance the sleeve G not only acts as a means for preventing the vibration of the shaft, but as a support for a 105 stationary guard H. The workman can rest his hand directly against this guard without being in any danger of having his hand lacerated, since this guard H does not revolve with the cutter. The result is that a 110 workman is able to finish a larger number of shoes in a given time than he is where

he has to be more careful in the handling of the stock, for fear of injury. Owing to the smooth finish given the edge of the sole, subsequent operation such as the ironing of 5 the edge may be omitted. This results in a further economy in making the shoe.

It is obvious that other means of attachment of the sleeve G to the bearing extension b, as well as other forms of supporting mechanism for the shaft E, might be 10 used without departing in the least from the spirit and scope of the invention.

I claim:—

1. In an edge trimming device, a revolvable shaft, a cutter carried by the shaft at 15 one end thereof, a stationary bearing for said shaft, having an extension, a sleeve secured to said extension for preventing the vibration of the shaft in a direction at right 20 angles to its axis, and a stationary guard or shield secured to said sleeve and having a portion extending over one edge of said cutter.

2. In an edge trimming device, a revolvable shaft, a cutter carried by the shaft at 25 one end thereof, a stationary bearing for said shaft, having an extension, a sleeve secured to said extension for preventing the vibration of the shaft in a direction at right 30 angles to its axis, a stationary guard or shield secured to said sleeve and having a

portion extending over one edge of said cutter, and means for adjusting the position of said guard on said sleeve relatively to said cutter, and for securing it in its adjusted 35 position.

3. In an edge trimming device, a support, bearings carried thereby, a shaft rotatably disposed in said bearings, one of 40 said bearings having an extension, a cutter carried by said shaft at one end thereof, means secured to said extension and arranged to engage said shaft for preventing the vibration thereof in a direction at right 45 angles to its axis, and a shield or guard rigidly secured to said means and arranged to extend over a portion of the cutter.

4. In an edge trimming device, a base or support, bearings carried by said base, one of 50 said bearings being extended, a rotatable shaft disposed in said bearings, a cutter carried at one end of said shaft, a sleeve arranged to fit over said shaft and having an enlarged portion arranged to engage and to be secured to said bearing extension, and 55 a second sleeve fitting over said first named sleeve and adjustably secured thereto, said second sleeve having a flange arranged to extend over a portion of the cutter and to constitute a guard therefor.

AMBROSE F. WERTMAN.
